UNITED STATES PATENT OFFICE.

ERNEST DAVIS, OF SYRACUSE, NEW YORK, ASSIGNOR TO THE PROSPERITY COMPANY INC., OF SYRACUSE, NEW YORK, A CORPORATION OF NEW YORK.

ACTUATING MECHANISM OR MECHANICAL MOVEMENT FOR PRESSING MACHINES.

Application filed April 9, 1926. Serial No. 100,985.

REISSUED

This invention relates to pressing machines and has for its object a particularly simple, compact and efficient actuating mechanism for the movable element or press head of the machine whereby a powerful actuating mechanism can be located within a comparatively small space or within the base of the pressing machine.

The invention consists in the novel features 10 and in the combinations and constructions hereinafter set forth and claimed.

In describing this invention, reference is had to the accompanying drawings in which like characters designate corresponding parts 15 in all the views.

Figure 1 is a side elevation, partly in section, of a pressing machine embodying my invention.

Figure 2 is a front elevation of parts seen 20 in Figure 1.

Figure 3 is an enlarged fragmentary sectional view showing the actuating mechanism in plan view.

Figure 4 is an enlarged fragmentary side 25 elevation of a portion of the actuating mechanism.

This mechanism comprises, generally, a reciprocating prime mover, a driven element and connections between the prime mover 30 and the driven element whereby the motion of the prime mover is first increased to effect a fast and comparatively great movement of the driven element and is thereafter reduced to effect a powerful but short movement of 35 the driven element upon a long movement of the prime mover.

The actuating mechanism is here shown as embodied in a pressing machine of the type used for pressing clothes and laundry, and 40 the pressing machine here shown, in which my invention is embodied comprises a buck 1 and a head 2 movable toward and from the buck, the buck being mounted upon a bracket or goose neck 3 which in turn is mounted upon a base 4 and the head being carried by the forward arm of a yoke or lever 5 pivoted between its ends at 6 to an upright rising from the frame and having its other arm 7 extending into the frame and connected to the actuating mechanism. This lever constitutes the 45 driven element.

The base 4 is formed hollow and the actuating mechanism is located therein and also the base 4 is mountable upon a table or bench 8. 50 The base and the construction of the pressing

machine, per se, forms no part of this invention but forms the subject matter of another application, the subject matter of this application being the actuating mechanism for the lever 7.

The prime mover is a reciprocating element as a piston rod 9 connected to a piston movable in a cylinder 10, the cylinder 10 and the rod 9 being here shown as arranged in horizontal position and extending forwardly and rearwardly in the hollow base 4. The connections between the rod 9 and the driven element or lever 5 which connections first increase the motion of the rod 9 and then reduce it, comprises a rotatable member here shown 60 as a gear 11 mounted on a suitable transverse stud at the outer end of the piston rod 9 and a link 12 mounted at one end on an eccentric pin 13 on the gear 11 and pivoted at its other end at 14 to the lower end of the lever 5. 65 Thus, the gear moves reciprocally with the rod 9. Means is provided for rolling the gear as a rack 15 meshing with the gear. As here shown, there are two gears mounted on opposite sides of the piston rod and each mesh 70 with the rack 15.

In operation, as best seen in Figure 4, the movement of the piston rod is increased during the initial movement thereof by the fact that the eccentric pin 13 is carried during the 75 rolling of the gear forwardly in the same direction as the rod is moving, so that the lever 5 partakes of the movement of the rod plus the rolling movement of the gear and the head 2 is brought down toward the buck 1 quickly. When the head 2 is brought down on the buck, the gear 11 has made substantially a half revolution as seen in Figure 1 and during the remainder of the power stroke of the piston which is comparatively long, the eccentric pin 13 moves rearwardly so that the movement of the lever 9 is the difference between the movement of the rod and the movement of the pin 13. Hence, the motion of the piston rod is transferred through a reduction 80 leverage so that a comparatively long movement of the piston is converted into a powerful short movement of the press head.

The cylinder is preferably a single acting cylinder and the flow of air or other motive fluid thereof is controlled in any suitable manner as by handles designated 16, there being two handles both of which must be operated during the closing of the press in order to keep both hands out of danger of 85 100 105 110

being caught in the press. The control of the motive fluid to the cylinder forms no part of this invention and is unnecessary to an understanding thereof.

- 5 The press is opened and the parts restored to their starting positions by a counterbalance spring 17 suitably connected to a shaft 18 to turn the same, the shaft having a winding drum 19 thereon which is connected by a cable 10 to the lower arm of the lever 5. During the closing of the press by power, obviously, the spring will be tensioned and when the power is released in the cylinder 10, the spring will react and open the press.
- 10 15 The actuating mechanism here shown is particularly adapted to be mounted in a small space as the base of the pressing machine shown herein.
- What I claim is:
- 20 1. An actuating mechanism comprising a reciprocating prime mover, an oscillating driven element, connections between the prime mover and the driven element comprising a gear mounted on the reciprocating prime mover and having a rocking movement, an eccentric pin on the gear arranged when in starting position between the axis of the gear and the prime mover and movable through more than one half of a revolution and approximately three quarters of a revolution during the rocking of the gear and the movement of the prime mover in one direction, means for rocking the gear comprising a stationary rack with which the pinion meshes and a link connecting the eccentric pin and the oscillating driven element.
- 25 30 35 2. A pressing machine comprising a base, a buck mounted on the base, a head movable

toward and from the buck, a lever carrying the head, the lever being pivoted to the base in the rear of the buck, means for actuating the lever comprising a cylinder arranged in horizontal position in the frame beneath the buck, a piston movable in the cylinder and having a reciprocally movable rod, the lever supporting the head having a downwardly extending arm, and motion transmitting mechanism between the rod and said arm including an element movable with the rod and also relatively thereto during the movement of the rod and means connecting said element and the lever arm to transmit the combined movement of said element with the rod plus the relative movement of said element to the lever arm.

3. A pressing machine comprising a hollow base, a buck mounted on the base, a head movable toward and from the base, a lever carrying the head pivoted intermediate of its ends to the base and having an arm extending into the base, actuating means for said lever located in the base including a reciprocating prime mover and connections between the prime mover and said arm comprising a rotatable member movable with the prime mover during the reciprocating movement thereof, a link pivoted at one end eccentrically to the rotatable member and at its other end to said arm and means for rolling said member during the reciprocating movement thereof.

In testimony whereof, I have hereunto signed my name, at Syracuse, in the county of Onondaga and in the State of New York, this 6th day of April, 1926.

ERNEST DAVIS.
